UNITED STATES PATENT OFFICE

109,561

DESIGN FOR A COAT

Salvatore Lo Prete, New York, N. Y.

Application April 7, 1938, Serial No. 76,337

Term of patent 3½ years

To all whom it may concern:

Be it known that I, Salvatore Lo Prete, a citizen of the United States and residing in Manhattan, in the city, county, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

The shaded portions represent fur.

I claim:

The ornamental design for a coat, substantially as shown and described.

SALVATORE LO PRETE.
